UNITED STATES PATENT OFFICE.

HARRY G. NORWOOD, OF BALTIMORE, MARYLAND, ASSIGNOR, BY DIRECT AND MESNE ASSIGNMENTS, OF ONE-HALF TO NAPOLEON B. LOBE AND S. BURNS RATCLIFFE, BOTH OF BALTIMORE, MARYLAND, TRADING AS N. B. LOBE & CO., OF BALTIMORE, MARYLAND, AND ONE-FOURTH TO EMIL J. KLEMM AND ONE-FOURTH TO EDWARD WISCHMEYER, JR., BOTH OF BALTIMORE, MARYLAND.

RAILROAD-SPIKE.

1,332,059.

Specification of Letters Patent. Patented Feb. 24, 1920.

Application filed November 29, 1918. Serial No. 264,551.

To all whom it may concern:

Be it known that I, HARRY G. NORWOOD, a citizen of the United States, residing at Baltimore, in the State of Maryland, have 5 invented certain new and useful Improvements in Railroad-Spikes; and I do hereby declare the following to be a full, clear, and exact description of the invention, such as will enable others skilled in the art to which 10 it appertains to make and use the same.

My invention relates to railroad spikes.

One object of my invention is to produce a railroad spike which can be driven readily within the tie.

15 Another object of my invention is to produce a railroad spike which can be quickly secured within the tie after it is driven therein.

Another object of my invention is to shape 20 the entering end of said spike so that splitting of the tie will be avoided.

Another object of my invention is to shape the head of said spike so that the motion which secures said spike within the tie will 25 also cause said head to grip the rail.

Another object of my invention is to provide means on said spike for sealing the top of the hole formed by driving said spike into said tie so that the ingress of water to 30 said hole is in a large degree prevented.

In the drawings:—

Figure 1 is a view showing a portion of a rail, a portion of a tie, both in section, with 35 one of my improved spikes in place in said tie. The spike is shown in the position in which it holds the rail to the tie.

Fig. 2 is a view similar to Fig. 1, but the spike is shown in the position it occupies when it has been driven into the tie and before 40 it is turned into the holding position.

Fig. 3 is a section of the spike shown in Fig. 1 as taken along the line 3—3 in said figure looking in the direction of the arrows.

45 Fig. 4 is a view of the parts shown in Fig. 1 looking in the direction of the arrow 4 in said figure.

Fig. 5 is a view of the spike shown in Fig. 1 looking in the direction of the arrow 50 5 in said figure.

Fig. 6 is a partial view of an alternative

form of body which may be used in lieu of the body shown in Figs. 1 and 2.

In the drawings:—

10 represents an ordinary tie such as is used in the construction of railroads, 11 represents the web and 12, the lower flange of any approved form of rail. 13 is one form of my improved railroad spike.

The spike 13 has a chisel edge 14 where 60 the flat surfaces 15—15 meet at an acute angle, as shown in Fig. 2. The flat surfaces 15—15 extend from the chisel edge 14 up to the first pair of trammel teeth 16—16.

65 The trammel teeth 16—16 are formed integrally with the shank 17 of the spike 13 and the upper and lower surfaces, such as 18—18, of the trammel teeth 16—16 are angularly disposed with reference to the shank 17, as shown in Fig. 1, and said surfaces 70 meet and form the substantially semi-circular sharp edges 19—19. The shank 17 extends slightly below the trammel teeth 16—16 and a groove such as 20 is turned in said shank for a purpose hereinafter explained.

75 Other trammel teeth, such as 21—21, upon the spike 13 are shaped similarly to the teeth 16—16. There may be any suitable number of teeth such as 21—21 formed upon the shank 17 in addition to the lowest teeth 16—16. Above the uppermost trammel teeth 22—22 the shank 17 is provided with a tapered shank 23 for a purpose hereinafter explained.

85 The head of the spike 13 comprises the lenticularly shaped top 24, the parallel sides 25—25, the curved end 26, the angularly disposed faces 27—27 and the flat end 28.

The bottom of the head is formed by the 90 helically shaped surface 29 for a purpose hereinafter explained.

In the variation shown in Fig. 6, the shank 30 is shaped the same as the shank 17 in Fig. 1, but the teeth 31—31 have flat surfaces such as 32—32 at the top thereof; the lower surfaces 33—33 of the teeth 31—31 are angularly disposed, the same as the surfaces 18—18 of the teeth 16—16 shown in Fig. 1. The junction of the flat surfaces 95 32—32 with the angularly disposed surfaces 33—33 forms semi-circularly shaped edges 100 33—33.

such as the edges 19—19 shown in Figs. 1, 2, 3 and 5.

All other parts of a spike which includes the variations shown in Fig. 6 are formed 5 as shown in Figs. 1 to 5 inclusive.

The manner of use and the operation of the spike shown in Figs. 1 to 5 are as follows:—

The rail is to be placed in position with 10 its flange resting upon the tie 10, the grain of the wood composing the latter running in the direction shown in Fig. 4. The spike 13 is then to be held upon the upper surface of the tie 10 with the chisel edge across 15 the grain of said tie. The lenticular top 24 is then to be struck with a hammer until the spike 13 is driven into the tie 10 to the position shown in Fig. 2 with the side of the helically shaped bottom 29 resting upon the 20 upper surface of the flange 12 and the upper portion of the taper 23 in contact with the edge of the flange 12. In this position of the spike the head will occupy the position shown dotted in Fig. 4.

25 A wrench is then to be applied to the flat surfaces 25—25 of the head of the spike 13 and said spike is to be turned from the position shown dotted in Fig. 4 to the position shown by full lines in said figure. This 30 will turn the spike 13 from the position shown in Fig. 2 to that shown in Fig. 1.

When the spike 13 is turned as just described, the teeth 16—16, 21—21 and 22—22 will cut into the wood composing the tie 10 35 and will thus prevent any longitudinal movement of said spike with reference to said tie. At the same time, the portion of the helically shaped bottom, shown at the left in Fig. 1 and at the front in Fig. 2, 40 will engage the upper surface of the flange 12 and will press the lower surface of said flange tightly against the upper surface of the tie 10.

The groove 20 is provided in the lower 45 surface of the shank 17 in order to reduce the resistance of the flat surfaces 15—15 to the aforesaid turning.

When the spike 13 is driven in to the position shown in Fig. 2 the taper 23 is 50 caused to fit tightly against the adjacent fibers of the tie 10 and thus serves to act as a stopper to prevent the ingress of water

within the hole formed when said spike is driven into said tie, thus insuring that the fibers of the tie 10 surrounding the shank 55 17 and the teeth 16—16, 21—21 and 22—22 shall be kept free from moisture, whereby deterioration of said fibers is avoided.

A spike comprising the variation shown 60 in Fig. 6 is used in the manner just described and its operation is as just described.

I claim:—

1. In a railroad spike, the combination 65 with a shank, and an elongated head on one end of said shank, of a helically shaped bottom on said head, and a chisel edge on the other end of said shank parallel to the length of said head.

2. In a railroad spike, the combination 70 with a shank, of a head on one end of said shank, a chisel edge on the other end of said shank, and a groove in said shank adjacent to said edge.

3. In a railroad spike, the combination 75 with an approximately cylindrical shank, a head on one end of said shank, and an entering wedge on the other end of said shank, of a plurality of diametrically opposed trammel teeth formed on said shank, 80 the edges of said teeth being in the same plane.

4. In a railroad spike, the combination 85 with an approximately cylindrical shank, a head on one end of said shank, and an entering wedge on the other end of said shank, of a plurality of trammel teeth 90 formed on said shank, the upper surfaces of said teeth being flat and the lower surfaces of said teeth being angularly disposed to said flat surfaces and meeting them in approximately semi-circular edges at the periphery of said teeth.

5. In a railroad spike, the combination 95 with a shank, of a head on one end of said shank, a chisel edge on the other end of said shank, a groove in said shank adjacent to said edge, a tapered part on said shank beginning at said head and extending toward the other end of said shank a part 100 of its length, and a plurality of trammel teeth formed on said shank.

In testimony whereof I affix my signature.
HARRY G. NORWOOD.
